HARVEY C. HAYES, OF WASHINGTON, DISTRICT OF COLUMBIA

APPARATUS FOR TRANSFORMING SOUND INTO ELECTRICAL ENERGY

Application filed June 30, 1924. Serial No. 723,427.

(GRANTED UNDER THE ACT OF MARCH 3, 1883, AS AMENDED APRIL 30, 1928; 370 O. G. 757)

While my invention relates generally to the transmission of sound by means of radio or telephone circuits, it relates more particularly to a means for transforming sound energy into electrical energy and has for an object the employment of transforming devices wherein the efficiency of transformation is constant and independent of its intensity or pitch of the sound.

10 Another object of my invention is the employment of the viscosity of air for both driving and damping the motion of the movable member.

15 A further object of my invention is the transformation of sound energy into electrical energy with a minimum of distortion.

In the case of transmitters, efforts to accomplish these results have been directed to the use of diaphragms stretched to such a tension 20 that the natural or fundamental resonant frequency will be well above the range of frequency of the sounds to be transmitted. Under such conditions the higher harmonic frequencies will not be troublesome and the vi-

25 brations of the diaphragm produced by the impinging sound waves will be true forced vibrations and hence will have an amplitude of motion very approximately proportional to that of the sound waves causing the motion.

30 The diaphragm may serve to operate one electrode of a microphone, or as one electrode of an electrostatic condenser, or as part of the magnetic circuit of a magnetophone in such a way as to produce small variations of electrical potential that can be utilized for energizing an electrical circuit, or for controlling the grid of a vacuum tube amplifier. The potential variation caused by the motion of the diaphragm will be extremely small in any 35 case for the reason that any motion of the diaphragm from the position of rest introduces such large restoring forces that the amplitude of motion is always very slight.

40 My invention consists substantially in the construction, combination and arrangement of parts associated therewith or as will be more fully hereinafter set forth as shown by the accompanying drawings and finally 45 pointed out in the appended claims.

50 Reference is to be had to the accompany-

ing drawings forming a part of this specification in which like reference characters indicate corresponding parts throughout the several views and in which:—Figure 1, is a plan view of one embodiment of my invention, and Fig. 2 is a sectional view on the line 2—2 of Fig. 1.

55 Referring to the drawings, the letters N and S indicate the two poles of a strong magnet and the numerals 1 and 2 indicate the terminals of a fine wire filament or ribbon shaped linear conductor 5, suspended between the jaws of the magnet. For concentrating and directing the sound waves through the gap between the pole pieces and across the 60 conducting filament or ribbon, a small mouthpiece, 3 may be employed, while on the side opposite the mouthpiece, the conducting filament or ribbon may be shielded from extraneous sounds and air draughts by means of a 65 small chamber 4, which also may serve for tuning when provided with means for adjusting the volume as shown by numeral 6.

70 The principle under which my invention operates is as follows. The diameter of the 75 conducting filament or filaments, as several can be threaded through the magnetic gap between the pole pieces of the magnet and connected either in series or parallel, is so small that the ratio of its area is great as 80 compared with its mass, and as a result the viscous forces become great as compared with the accelerating forces whenever air tends to move around the filaments, or conversely, whenever the filament tends to move with 85 the air surrounding it, and when sound waves enter the magnetic gap they force the filament to move back and forth across the magnetic field with a frequency and amplitude proportional to the sound waves. This motion, in turn, generates electromotive forces along the filament proportional to the amplitude and frequency of the sound waves. The 90 viscous forces which cause the filament to follow the motion of the medium transferring the sound waves, also check the motion of the filament when its slight inertia tends to carry it forward. This results in highly 95 damping the motion of the filaments and thus prevents distortion due to resonance. In 100

order to obtain this result, the filament should be made of extremely light wire and be suspended without tension.

For transmitting the human voice or for broadcasting radio concerts, the filaments should be so dimensioned and mounted that their motion will be aperiodic. The electro-motive forces generated by the moving filaments will be proportional to the amplitude of the sound waves and the transformation from sound energy to electrical energy will be accomplished without distortion. By the utilization of the pull exerted upon the filaments by the viscosity of the fluid flowing around the filament rather than the utilization of the impact of the fluid against the flat surface of the ribbon conductors I have produced a microphone that is more faithful to the true transformation of sonic undulations into electrical energy.

It will be understood that the above description and accompanying drawings comprehend only the general and preferred embodiment of my invention and that minor detail changes in the construction and arrangement of parts may be made within the scope of the appended claims without sacrificing any of the advantages of my invention.

The invention herein described may be manufactured and used by or for the Government of the United States for governmental purposes without the payment to me of any royalty thereon or therefor.

Having described my invention, what I claim is:

1. An apparatus for transforming sound into electrical energy, comprising a magnet having a magnetic gap between its pole pieces, means for directing sound waves between the pole pieces of the magnet, a plurality of linear conductors disposed in parallel within the magnetic gap and substantially in planes at right angles to the passage of the sound waves through said magnetic gap, and electrical connections for said conductors for the utilization of the voltage generated therein by movement of said conductors within said magnetic gap.

2. An apparatus for transforming sound into electrical energy, comprising a magnet having a magnetic gap between its pole pieces, means for directing sound waves between the pole pieces of the magnet and a plurality of conductors disposed within the magnetic gap, said conductors having an area large in comparison to their mass and forming substantially no planar obstruction to the passage of sound waves through the magnetic gap and substantially in a plane at right angles to the passage of the sound waves through said magnetic gap, and electrical connections for said conductors for the utilization of the voltage generated therein by movement of said conductors within said magnetic gap.

3. An apparatus for transforming sound into electrical energy, comprising a magnet having a magnetic gap between its pole pieces, means for directing sound waves between the pole pieces of the magnet and a plurality of conductors disposed within the magnetic gap, said conductors having an area large in comparison to their mass and forming substantially no planar obstruction to the passage of sound waves through the magnetic gap, and of such size that they produce substantially no diminution of the volume of the magnetic gap and substantially in a plane at right angles to the passage of the sound waves through said magnetic gap, and electrical connections for said conductors for the utilization of the voltage generated therein by movement of said conductors within said magnetic gap.

4. An apparatus for transforming sound into electrical energy, comprising a magnet having a magnetic gap between its pole pieces, a fluid within the magnetic gap, means for directing sound waves through said fluid between the pole pieces of the magnet, and a plurality of linear conductors disposed within the magnetic gap in contact with said fluid and substantially in planes at right angles to the passage of the sound waves through said magnetic gap, and electrical connections for said conductors for the utilization of the voltage generated therein by movement of said conductors within said magnetic gap.

5. An apparatus for transforming sound into electrical energy, comprising a magnet having a magnetic gap between its pole pieces, a fluid within the magnetic gap, means for directing sound waves between the pole pieces of the magnet and a plurality of conductors disposed within the magnetic gap, said conductors having a mass of inertia small as compared to the area of the conductor and the viscosity of the fluid within the magnetic gap, and substantially in a plane at right angles to the passage of the sound waves through said magnetic gap, and electrical connections for said conductors for the utilization of the voltage generated therein by movement of said conductors within said magnetic gap.

6. An apparatus for transforming sound into electrical energy, comprising the combination of a magnet having a magnetic gap, a fluid within the magnetic gap, a ribbon-shaped conductor disposed within the magnetic gap, means for directing sound undulations through the fluid within the magnetic gap and across said conductor, and electrical connections for said conductors for the utilization of the voltage generated therein by movement of said conductors within said magnetic gap.

7. An apparatus for transforming sound into electrical energy, comprising the combination of a magnet having a magnetic gap, a

fluid within the magnetic gap, a ribbon-shaped conductor disposed within the magnetic gap, means for directing sound undulations through the fluid within the magnetic gap and across said conductor, the effect of mass of said conductor upon the motion of said conductor being small as compared to the effect of the area of the conductor and the effect of the viscosity of the fluid, and electrical connections for said conductor for the utilization of the voltage generated therein by movement of said conductor within said magnetic gap.
